CLAIM

An ornamental design for an exterior surface configuration for an engine hood light, as shown and described.

DESCRIPTION

FIG. 1 is a perspective view of an exterior surface configuration for an engine hood light unit. The drawings and descriptions represent the left side embodiment. The design also contemplates a mirror symmetrical embodiment on the opposite side of the vehicle. The dash line included denotes environment and is not part of the claimed design.

FIG. 2 is a front view thereof;

FIG. 3 is a side view thereof; and,

FIG. 4 is a top view thereof.
